FILM-PROCESSING APPARATUS WHICH EMPLOYS LIQUID-CARRYING CONTAINERS

Edwin H. Land, Cambridge, Mass., assignor to
Polaroid Corporation, Cambridge, Mass., a corporation of Delaware

Application February 21, 1951; Serial No. 212,167

13. Claims. (Cl. 95—89).

1

This invention relates to photography and more particularly to novel photographic apparatus, such as a camera, wherein a photosensitive sheet material may be processed by being brought into face-to-face relationship with another sheet material and by having the liquid of a container carried by one of said sheets released between said sheets. In a preferred form of the apparatus, negative and positive images are concurrently produced in the two sheets and there is also preferably provided a dark chamber in the apparatus into which the processed sheets are fed, the image-forming reactions being carried out while the sheets remain in this dark chamber.

The principal object of the present invention is to provide improved means in such apparatus to insure that the liquid-carrying container will be opened to permit the release of the processing liquid contained therein.

Another object of the invention is to provide such improved opening means operating independently of the processing means.

Still another object of the invention is to provide improved means for presenting said liquid-carrying containers to the action of said opening means prior to submitting said containers to the action of said processing means.

These and other objects of the invention will in part be obvious and will in part appear hereinafter.

The invention accordingly comprises the apparatus possessing the construction, combination of elements and arrangements of parts which are shown and described in the following detailed disclosure, and the scope of the application of which will be indicated in the claims.

For a more complete understanding of the nature and objects of the invention, reference should be had to the following detailed description taken in connection with the accompanying drawings wherein:

Figure 1 is a diagrammatic fragmentary vertical sectional view of a preferred modification of the invention as embodied in a hand-held camera;

Fig. 2 is a fragmentary sectional view taken along the line 2—2 of Fig. 1;

Fig. 3 is a fragmentary sectional view similar to Fig. 1, but illustrating another modification of the present invention;

Fig. 4 is a view similar to Fig. 3 but illustrating a still further modification of the invention; and

Fig. 5 is a fragmentary view of a container-carrying sheet.

2

In a preferred type of hand-held camera embodying the present invention and illustrated in the drawings, the camera comprises a front housing, a rear housing and a partition extending between these two housings. The camera is provided with means for holding the two sheets. In a preferred form, there is one such means, adjacent to one end of a camera, for holding a supply, such as a roll, of the photosensitive film, and means are provided, preferably adjacent to the other end of the camera, for holding a supply, such as a second roll, of sheetlike material. One of these rolls of sheet material preferably supports a plurality of liquid-carrying containers. An exposure opening is provided in the front housing and a door is included in the rear housing, the partition defining an exposure chamber with the front housing and defining a dark chamber with the rear housing, the door serving to provide access to the dark chamber. The camera also includes processing means, preferably comprising a pair of pressure-applying members positioned between the exposure opening and the second roll-holding means and arranged to release the processing liquid from the container and to spread this released liquid between the two sheetlike materials in superposition between the pressure-applying members.

This invention is primarily directed to means for opening the liquid-carrying containers preparatory to the release of processing liquid therefrom by said processing means. In a preferred form of the invention, the opening means comprises a rotatable member arranged to engage a longitudinal edge portion of the container to open the container before the pressure-applying members of the processing means apply pressure thereto. As illustrated, the opening means comprises a rotatable knife member arranged for movement in engagement with a longitudinal edge portion of the container to sever said edge portion from the body of the container, thus permitting the liquid contained therein to be released and spread on the superposed sheets when pressure is applied thereto by said processing means.

The illustrated embodiments of the present invention are illustrated herein as applied to a hand-held camera of the type illustrated in the 50 United States Patent No. 2,491,769, granted December 20, 1949, on an application filed in the name of Charles O. Rolando. The camera comprises a front housing 10 and a rear housing 12 pivotally secured to the front housing by a hinge 14. The front housing 10 is provided with a

usual bellows 16 surrounding an exposure opening 18. The front of the bellows 16 is provided with the usual shutter housing (not shown). The camera is also provided with a light-tight chamber (not shown) holding a supply of sheet 20 having thereon a plurality of spaced photosensitive areas arranged successively to be brought into position below the exposure opening 18. The camera is also provided with a chamber 22 in which is supported a roll 26 of image-carrying sheet 28 having liquid-carrying containers 30 secured thereto at spaced intervals. The image-carrying sheet 28 passes from the roll 26 under a tension-applying member 32 having sides 34 which are arranged to engage opposite side edges of the sheet 28 and having the bottom of the member 32 between said sides 34 raised sufficiently to permit passage of the spaced liquid-carrying containers 30 thereunder without exerting any pressure thereon. The sheet 28 passes from the tension-applying member 32 past a suitable mechanism for opening the container 30 and between a pair of pressure rolls 36, 38 into a processing chamber. The photosensitive sheet 20 passes over the top of the roll 38 and is superposed on the sheet 28 between the rolls 36, 38. The roll 36 is rotatably supported in suitable bearings in the rear housing 12 and the roll 38 is rotatably supported in bearings formed in suitable members mounted in the front housing 10, which second roll is resiliently urged into pressure engagement with the other roll 36 by a spring-biased bar 41. Thus, when the camera is to be loaded and the rear housing 12 is swung about the hinge 14, the rolls 36, 38 are separated to permit insertion of the leaders of sheets 20 and 28 therebetween.

The construction shown in Fig. 1 illustrates a preferred embodiment of the present invention for opening the liquid-carrying containers 30 carried by the image-carrying sheet 28. After the sheet 28 passes from below the tension-applying member 32, it passes upwardly over a suitable roll 40 mounted in suitable bearings in the sides of rear housing 12 and below a shaft 42 supported in suitable bearings in the front housing 10 and having thereon rollers 44 arranged to engage the opposite marginal edges of the sheet 28. The roll 40 and the cooperating rolls 44 are so positioned relatively to the member 32 and the processing or pressure rolls 36, 38 that the sheet 28 is flexed and a container 30 fixed to the sheet 28 is caused to swing upwardly relatively to the sheet 28 and into engagement with a suitable stationary member, such as anvil 43, fixed to the side walls of the front housing 10 and extending transversely of the front housing 10, as shown most clearly in Fig. 2. The member 43 is provided with a V-shaped groove 46 which cooperates with a rotary knife 48, as will later be described.

As is usual in cameras of the type described herein, the photosensitive sheet 20 preferably has a support or base, for example of paper, upon which is mounted the photosensitive silver halide emulsion which provides the areas or frames capable of being photoexposed in opening 18. With such an emulsion, the image-carrying sheet 28 preferably comprises baryta paper having the containers 30 secured thereto at predetermined spaced intervals. The processing liquid carried by the containers 30 preferably comprises a viscous alkaline aqueous solution of a developer, a silver halide solvent and a film-forming material. The container 30 is preferably formed of a paper-

backed metal foil coated at the inner surface thereof with a synthetic resin, such as polyvinyl butyral, which is inert to alkalies. The paper-backed metal foil is preferably folded on itself to form a relatively long container which is sealed at its side edge portions. After a suitable quantity of processing liquid is placed in the container 30, the edge opposite to the folded edge is sealed by the use of a suitable adhesive which is inert to alkalies.

When the rotary knife 48 is brought into engagement with the container 30, it is arranged to cut entirely through the two layers of the container material over the major portion of said container. Thus, the container 30 is effectively opened to permit release of the processing liquid contained therein and the entire container 30 passes as a unit between the processing rolls 36, 38 when the sheets 20, 28 are moved into the processing chamber.

The rotary knife 48 is rotatably mounted on a lever 50 pivoted at 52 to a sliding block 54 having an opening therein through which extends a supporting rod 56 secured at each end to the side walls of the front housing 10. The lever 50 carries at its free end a roll 55 which is arranged, when the knife assembly is returned to initial position, to move the rotary knife 48 out of contact with the container 30. The block 54 is provided with a pair of oppositely disposed arms 60, 62. The arm 60 has secured thereto one end of a tension spring 64 which is connected at its other end to an arm 66 on the lever 50 and which acts to bias the knife 48 into cutting engagement with the container 30. The sliding block 54 and the parts connected thereto are normally spring-urged toward the left of the front housing 10, as viewed in Fig. 2, by a tension spring 68 connected at one end to the arm 62 on the sliding block 54 and at its other end to bracket 70 fixed to the left side of the front housing 10 as viewed in Fig. 2. When the cutting device is retracted by the spring 68, the roll 55 rides on the cam surface 71 formed at the left-hand end of the member 43 and moves the knife 48 out of engagement with the container 30 as it reaches the left-hand edge of the slot 46. The block 54 and the parts carried thereby are moved in the opposite direction against the tension of the spring 68 by a rod 72 secured at one end to the block 54 and extending parallel to the supporting rod 56 and through a suitable opening in the right-hand side of the front housing 10. The rod 72 is provided at its outer end with a knob 74, forming a convenient means for the operator to grasp when moving the knife assembly to the right to sever or open the container 30. The knife assembly is pulled to the right as viewed in Fig. 2 until the block 54 engages the right-hand side of the front housing 10. The parts are so arranged that the block 54 is brought against the side of the front housing 10 as the knife 48 reaches the right-hand end of the slot 46. Thus, the major portion of the sealed edge of the container 30 is severed but the sealed edge still is held against displacement as the container 30 passes between the flexing rolls 40, 44 and the processing rolls 36, 38.

The modification illustrated in Fig. 3 is similar to the one shown in Fig. 1. The knife assembly and the stationary cooperating cutter bar 43 are substantially the same but the entire assembly is moved closer to the processing rolls 36, 38 and the flexing rolls 40 and 44 are omitted. The container 30 is secured to the image or positive sheet

20 in the usual manner as by a suitable adhesive tape 78. It will be noted that the container is illustrated as being somewhat curved. Since the container is formed of paper-backed metal foil, it will assume and retain generally the curvature of the roll of which it is a part. Thus when the sheet 28 is stretched straight between the tension-applying member 32 and the processing rolls 36, 38 the container 30 will swing into the relative position shown in Fig. 3 and will be properly positioned for the container-severing operation hereinbefore described.

The modification illustrated in Fig. 4 is also similar to the modification illustrated in Fig. 1. The knife assembly and the cooperating stationary cutter bar 43 are in substantially the same position relatively to the processing rolls 36, 38. Positive means for properly positioning the container 30 for being acted upon by the cutting means is provided. Said positioning means comprises a pair of resilient strips 78 formed of suitable spring material secured to the rear housing 12 adjacent to the opposite side edges of the positive or second sheet 28. The strips 78 extend upwardly and are inclined toward the processing rolls 36 and 38. The strips 78 engage tabs 80 (Fig. 5) on opposite sides of the container 30 and guide the unattached sealed edge portion thereof into the position shown in Fig. 4 as the sheets 20, 28 are moved into the processing chamber.

Although the foregoing structure has been described by way of example as being embodied in a hand-held camera, it is to be expressly understood that the novel combination of the container-opening means and the liquid-spreading means, as hereinabove described, may be used for many other photographic purposes, for example in apparatus for copying documents or for just processing photosensitive film that has been exposed elsewhere than in said apparatus.

It is believed to be apparent also that the dark processing chamber which receives the two sheets after the liquid is spread therebetween is not essential to the proper functioning of the apparatus where the two sheets are opaque to light actinic to the photosensitive layer. In the latter event, the superposed sheets may be ejected directly from the apparatus into the open without danger of fogging the photosensitive layer. The term "photosensitive" as used herein is to be understood as covering silver halide emulsions and other photosensitive materials which are actinic not only in the visible and near-visible light but also to nuclear radiation so that the devices of the present invention are useful for such purposes as measuring dosages of nuclear radiation.

While preferred forms of the invention have been described and shown herein, it should be understood that various other modifications of the specific constructions shown may be accomplished without departing from the scope of the invention.

Since certain changes may be made in the above apparatus without departing from the scope of the invention herein involved, it is intended that all matter contained in the above description or shown in the accompanying drawings shall be interpreted as illustrative and not in a limiting sense.

What is claimed is:

1. A photographic apparatus for processing a photosensitive first sheet in conjunction with a second sheet and in conjunction with at least a container affixed to one of said first and sec-

ond sheets, said container having a processing liquid therewithin and a section providing a sealed mouth, said apparatus comprising a pair of rollers for applying opposed compressional forces in the region therebetween, guide means providing one path for said one of said first and second sheets, said one path terminating in said region, guide means providing another path for the other of said first and second sheets, said other path terminating in said region, associated portions of said one sheet and said other sheet being adapted to be advanced along said one path and said other path, respectively, and through said region from one side thereof to the opposite side thereof, and means engageable with said container for unsealing said mouth, said last-mentioned means being located on said one side of and adjacent to said region and being clear of and adjacent to said one path, the last-mentioned means including an anvil having a surface against which said container is adapted to abut and an unsealing element cooperating with said anvil, said rollers when said associated portions are advanced through said region in superposed relation with said container therebetween being adapted to cause said processing liquid to be ejected from said container and to be spread between said associated portions.

2. A photographic apparatus for processing a photosensitive first sheet in conjunction with a second sheet and in conjunction with at least a container affixed to one of said first and second sheets, said container having a processing liquid therewithin and a section providing a sealed mouth, said apparatus comprising a pair of rollers for applying opposed compressional forces in the region therebetween, guide means providing one path for said one of said first and second sheets, said one path terminating in said region, guide means providing another path for the other of said first and second sheets, said other path terminating in said region, associated portions of said one sheet and said other sheet being adapted to be advanced along said one path and said other path, respectively, and through said region from one side thereof to the opposite side thereof, and means engageable with said section for unsealing said mouth, the last-mentioned means including an anvil having a surface against which said section is adapted to abut and a cutting element cooperating with said anvil for separating a portion of said section from the remainder thereof, said cutting element being mounted for movement in a third path which is on said one side of and adjacent to said region and is clear of and adjacent to said one path, said rollers when said associated portions are advanced through said region in superposed relation with said container therebetween being adapted to cause said processing liquid to be ejected from said container and to be spread between said associated portions.

3. A photographic apparatus for processing a photosensitive first sheet in conjunction with a second sheet and in conjunction with at least a container affixed at one of its edges to one of said sheets, said container having a processing liquid therewithin and a peripheral section at the edge thereof opposite said one edge, said peripheral section providing a sealed mouth, said apparatus comprising a pair of pressure-applying members defining a region therebetween, guide means providing one path for said one of said first and second sheets, said one path terminating in said region, guide means providing an-

other path for the other of said first and second sheets, said other path terminating in said region, associated portions of said first sheet and said second sheet being adapted to be advanced along said one path and said other path, respectively, and through said region from one side thereof to the opposite side thereof, and means engageable with said peripheral section for unsealing said mouth, the last-mentioned means including an anvil having a surface located on said one side of and adjacent to said region and clear of and adjacent to said one path, means located on said one side of and adjacent to said region for pivoting said container about said one edge thereof until said peripheral section abuts against said surface and means cooperating with said surface of said anvil for severing a portion of said peripheral section from the remainder thereof in order to substantially unseal said mouth, said members when said associated portions are advanced through said region in superposed relation with said container therebetween causing said processing liquid to be ejected from said container and to be spread between said associated portions.

4. A photographic apparatus for processing a photosensitive first sheet in conjunction with a second sheet and in conjunction with at least a container affixed at one of its edges to one of said sheets, said container having a processing liquid therewithin and a peripheral section at the edge thereof opposite said one edge, said peripheral section providing a sealed mouth, said apparatus comprising a pair of pressure-applying members defining a region therebetween, guide means providing one path for said one of said first and second sheets, said one path terminating in said region, guide means providing another path for the other of said first and second sheets, said other path terminating in said region, associated portions of said first sheet and said second sheet being adapted to be advanced along said one path and said other path, respectively, and through said region from one side thereof to the opposite side thereof, and means engageable with said peripheral section for unsealing said mouth, the last-mentioned means including an anvil having a surface located on said one side of and adjacent to said region, a pair of rollers located on said one side of and adjacent to said region, said pair of rollers being adapted to abut against opposite surfaces of said one sheet, said pair of rollers having axes lying substantially in a plane oblique to said opposite surfaces, said pair of rollers being adapted to pivot said container about said one edge thereof until said peripheral section abuts against said surface of said anvil and means cooperating with said anvil for severing a portion of said peripheral section from the remainder thereof in order to substantially unseal said mouth.

5. A photographic apparatus for processing a photosensitive first sheet in conjunction with a second sheet and in conjunction with at least a container, said container being affixed at one of its edges to one of said sheets, having a processing liquid therewithin, having a normally curved surface adjacent to one of said sheets and having a peripheral section providing a sealed mouth at the edge of said container opposite said one edge, said apparatus comprising a pair of pressure-applying members defining a region therebetween, guide means providing one path for said one of said first and second sheets,

said one path terminating in said region, guide means providing another path for the other of said first and second sheets, said other path terminating in said region, associated portions of said first sheet and said second sheet being adapted to be advanced along said one path and said other path, respectively, and through said region from one side thereof to the opposite side thereof, and means engageable with said peripheral section for unsealing said mouth, the last-mentioned means including an anvil having a surface located on said one side of and adjacent to said region, said normally curved surface causing said peripheral section to project outwardly from said one sheet so as to be adapted to abut against said surface of said anvil and means cooperating with said anvil for severing a portion of said peripheral section from the remainder thereof, said members when said associated portions are advanced through said region in superposed relation with said container therebetween causing said processing liquid to be ejected from said container and to be spread between said associated portion.

6. A photographic apparatus for processing a photosensitive first sheet in conjunction with a second sheet and in conjunction with at least a container, said container being affixed at one of its edges to one of said sheets, having a processing liquid therewithin, having a peripheral section providing a sealed mouth at the edge of said container opposite said one edge and having a tab extending from said edge of said container opposite said one edge, said apparatus comprising a pair of pressure-applying members defining a region therebetween, guide means providing one path for said one of said first and second sheets, said one path terminating in said region, guide means providing another path for the other of said first and second sheets, said other path terminating in said region, associated portions of said first sheet and said second sheet being adapted to be advanced along said one path and said other path, respectively, and through said region from one side thereof to the opposite side thereof, and means engageable with said peripheral section for unsealing said mouth, said last-mentioned means including an anvil having a surface located on said one side of and adjacent to said region, an arm positioned in said housing adjacent to said one path, said arm being adapted to engage said tab and thereby to pivot said container about said one edge thereof until said section abuts against said surface and cutting means cooperating with said surface for severing a portion of said section from the remainder thereof in order to substantially unseal said mouth, said members when said associated portions are advanced through said region in superposed relation with said container therebetween causing said processing liquid to be ejected from said container and to be spread between said associated portions.

7. A photographic apparatus for processing a photosensitive first sheet in conjunction with a second sheet and in conjunction with at least a container secured at one of its edges to one of said sheets, said container having a processing liquid therewithin and a peripheral section at the edge thereof opposite said one edge, said peripheral section providing a sealed mouth, said apparatus comprising one mounting means for carrying a supply of said one sheet, another mounting means for carrying a supply of said other sheet, a pair of pressure-applying members defining a

first region therebetween, guide means providing one path extending from said one mounting means to said first region, guide means providing another path extending from said other mounting means to said first region, associated portions of said one sheet and said other sheet being adapted to be advanced along said one path and said second path, respectively, and through said first region from one side thereof to the opposite side thereof, and means engageable with said peripheral section for unsealing said mouth, the last-mentioned means including an anvil having a surface, means for pivoting said container about said one edge until said peripheral section abuts against said surface and means cooperating with said anvil in a second region for severing a portion of said peripheral section from the remainder thereof, said second region being located on said one side of and adjacent to said first region and clear of and adjacent to said one path, said members when associated portions are advanced through said first region in superposed relation with said container therebetween being adapted to cause said processing liquid to be ejected from said container and to be spread between said associated portions.

8. A photographic apparatus for processing a photosensitive first sheet in conjunction with a second sheet and in conjunction with at least a container secured at one of its edges to one of said sheets, said container having a processing liquid therewithin and a peripheral section at the edge thereof opposite said one edge, said peripheral section providing a sealed mouth, said apparatus comprising one mounting means for carrying a supply of said one sheet, another mounting means for carrying a supply of said other sheet, a pair of pressure-applying members defining a first region therebetween, guide means providing one path extending from said one mounting means to said first region, guide means providing another path extending from said other mounting means to said first region, associated portions of said one sheet and said other sheet being adapted to be advanced along said one path and said other path, respectively, and through said first region from one side thereof to the opposite side thereof, and means engageable with said peripheral section for unsealing said mouth, the last-mentioned means including an anvil having a surface, means for pivoting said container about one edge until said peripheral section abuts against said surface and a cutter cooperating with said anvil in a second region, said cutter being mounted for transverse movement with respect to said paths for severing a portion of said peripheral section from the remainder thereof, said second region being located on said one side of and adjacent to said first region and clear of and adjacent to said one path, said members when said associated portions are advanced through said first region in superposed relation with said container therebetween being adapted to cause said processing liquid to be ejected from said container and to be spread between said associated portions.

9. A photographic apparatus for processing a photosensitive first sheet in conjunction with a second sheet and in conjunction with at least a container secured at one of its edges to one of said sheets, said container having a processing liquid therewithin and a peripheral section at the edge thereof opposite said one edge, said peripheral section providing a sealed mouth, said apparatus comprising one mounting means for

carrying a supply of said one sheet, another mounting means for carrying a supply of said other sheet, a pair of pressure-applying members defining a first region therebetween, guide means providing one path extending from said one mounting means to said first region, guide means providing another path extending from said other mounting means to said first region, associated portions of said one sheet and said other sheet being adapted to be advanced along said one path and said other path, respectively, and through said first region from one side thereof to the opposite side thereof, and means engageable with said peripheral section for unsealing said mouth, the last-mentioned means including an anvil having a surface, means for pivoting said container about said one edge thereof until said peripheral section abuts against said surface and a rotary cutter cooperating with said surface of said anvil 20 in a second region to sever a portion of said peripheral section from the remainder thereof, said second region being located on said one side of and adjacent to said first region and clear of and adjacent to said one path, said members when said associated portions are advanced through said first region in superposed relation with said container therebetween being adapted to cause said processing liquid to be ejected from said container and to be spread between said associated portions.

10. A photographic apparatus for processing a photographic sheet in conjunction with at least a container affixed at one edge to said sheet, said container having a processing liquid therewithin and a peripheral section at the edge thereof opposite said one edge, said peripheral section providing a sealed mouth, said apparatus comprising pressure-applying members for exerting opposed compressional forces in a first region, guide means providing a path for said photographic sheet, said path terminating in said first region, a portion of said sheet being adapted to be advanced along said path and through said first region from one side thereof to the opposite side thereof, and means engageable with said section for unsealing said mouth, the last-mentioned means including an anvil having a surface, means for pivoting said container about said one edge until said peripheral section abuts against said surface and means cooperating with said anvil in a second region for severing a portion of said peripheral section from the remainder thereof, said second region being located on said one side of and adjacent to said first region and clear of and adjacent to said path, said pressure-applying members when said portion is advanced through said first region being adapted to cause said processing liquid to be ejected from said container and to be spread upon said portion.

11. A photographic apparatus for processing a photosensitive sheet in conjunction with at least a container affixed at one edge to said sheet, said container having a processing liquid therewithin and a peripheral section at the edge thereof opposite said one edge, said peripheral section providing a sealed mouth, said apparatus comprising pressure-applying means for exerting opposed compressional forces in a first region, guide means providing a path for said photographic sheet, said path terminating in said first region, a portion of said sheet being adapted to be advanced along said path and through said first region from one side thereof to the opposite side thereof, and means engageable with said section for unsealing said mouth, the last-mentioned

means including an anvil having a surface, means for pivoting said container about said one edge until said peripheral section abuts against said surface, the last-mentioned means being located on said one side of and adjacent to said region and clear of and adjacent to said path and a cutting element cooperating with said anvil in said second region for severing a portion of said peripheral section from the remainder thereof, said second region being located on said one side of and adjacent to said first region and clear of and adjacent to said path, said pressure-applying members when said portion is advanced through said first region being adapted to cause said processing liquid to be ejected from said container and to be spread upon said portion.

12. A photographic apparatus for processing a photosensitive first sheet in conjunction with a second sheet and in conjunction with at least a container affixed to one of said first and second sheets, said container having a processing liquid therewithin and a section providing a sealed mouth, said apparatus comprising a pair of pressure-applying members for applying opposed compressional forces in the region therebetween, guide means providing one path for said one of said first and second sheets, said one path terminating in said region, guide means providing another path for the other of said first and second sheets, said other path terminating in said region, associated portions of said one sheet and said

other sheet being adapted to be advanced along said one path and said other path, respectively, and through said region from one side thereof to the opposite side thereof, and means engageable with said container for unsealing said mouth, said last-mentioned means being located on said one side of said region and adjacent to said one path, said last-mentioned means providing a surface against which said container is adapted to abut and including an unsealing element adapted to cooperate with said surface, said unsealing element being mounted for movement in a third path which is clear of said first and second paths, said pressure-applying members, when said associated portions are advanced through said region in superposed relation with said container therebetween, being adapted to cause said processing liquid to be ejected from the unsealed container and to be spread between said associated portions.

13. The photographic apparatus of claim 12 wherein said unsealing element is a cutting element.

EDWIN H. LAND.
